UNITED STATES PATENT OFFICE.

GEORGE HAVELL AND ALFRED G. WILLIAMS, OF NEWARK, NEW JERSEY.

DESIGN FOR A BICYCLE-LAMP.

SPECIFICATION forming part of Design No. 26,762, dated March 16, 1897.

Application filed October 15, 1896. Serial No. 609,029. Term of patent 7 years.

To all whom it may concern:

Be it known that we, GEORGE HAVELL and ALFRED G. WILLIAMS, citizens of the United States, residing at Newark, county of Essex, 5 State of New Jersey, have invented a certain new and useful Design for Bicycle-Lamps with Scalloped Ornaments, fully described and represented in the following specification and the accompanying drawings, forming a 10 part of the same.

The present invention relates to a design for a bicycle-lamp. Such lamps comprise a body and an oil-cup secured to such body.

The distinguishing feature of the design is 15 a scalloped ornament exhibited upon the rear end of a horizontal cylinder in the body of the lamp, upon the cap of the smoke-funnel, and upon the upper and lower sides of the oil-cup.

In the drawings, Figure 1 is a front elevation, and Fig. 2 a side elevation, of a bicycle-lamp embodying our design. Fig. 3 is a rear elevation of the lamp-body, and Fig. 4 a plan of the same.

The lamp-body embraces the following features: the horizontal cylinder A, having convex-lens projection B at the front end, and at 25 the rear end the scalloped boss D, projected therefrom and terminated by flat cylindrical boss E. From the upper side of the cylinder 30 A projects the flaring funnel F, having at the

top the scalloped cap G, terminated by the flat cylindrical boss H. From the lower side of the cylinder A projects the round neck I, to which the oil-cup is secured. The oil-cup is formed with horizontal central fillet J, above 35 and below which the body is scalloped, the upper scallops K curving inward to the neck I, and the lower scallops L curving inward to a flat cylindrical bottom boss M.

The essential features of the design for the 40 body are the scalloped projection at the rear end of the cylindrical body and the scalloped cap upon the top of the funnel.

The essential features of the design for the entire lamp are the scalloped boss at the rear 45 end of the cylindrical body, the scalloped cap upon the top of the funnel, and the lamp having the central fillet with scallops above and below the same.

What we claim is—

The design for a bicycle-lamp, as shown and described.

In testimony whereof we have hereunto set our hands in the presence of two subscribing witnesses.

GEORGE HAVELL.
ALFRED G. WILLIAMS.
